RAYON SPINNING

Neo S. Serinis, Gloucester, N. J., assignor to Imperial Rayon Corporation, Gloucester, N. J., a corporation of Delaware

Application June 23, 1937, Serial No. 149,818

7 Claims. (Cl. 18—8)

This invention relates to improvements in the manufacture of artificial fibers and more particularly to the continuous formation of rayon.

One of the principal objects of this invention 5 is to provide an improved means for starting the flow of artificial fibers from a spinneret.

Another object of the invention is to provide an improved apparatus for assuring a uniform substantially vertical feed of the fibers from the 10 spinneret to a central guide.

Further objects and advantages of the invention will appear from the following description of a preferred form of embodiment of my invention taken in connection with the attached drawing 15 illustrative thereof and in which

Figure 1 is a broken away perspective view of the precipitating tank in accordance with my invention.

Figure 2 is a view similar to Figure 1 showing 20 the spinneret in a second position.

Figure 3 is a plan view of the guide plate.

As is well-known in the preparation of artificial fibers, more particularly rayon, the cellulose product is forced through a suitable conduit generally 25 indicated at 10 in Figure 1 into a spinneret 12 from which the artificial fiber 14 discharges into a precipitating bath 15 thereby forming into the separate fibrous material.

In the preparation of artificial fibers and particularly rayon made by the cupro-ammonium process, I find it desirable to use a multiple number of spinnerets arranged annularly about a common center and with substantially uniform angular spacing. It is particularly desirable, however, to use some form of guide for the filaments as they precipitate and I have provided a fixed guide 17 suitably supported as by supports 18. This guide is preferably formed with a plurality of openings 19 and the spinnerets 12 are suitably 35 mounted on the common head 20 in a spaced angular fashion. Preferably the spinnerets 12 extend a slight distance above the head 20 and are preferably of a size equivalent to the openings 19 so that for starting purposes the head 20 may be 40 elevated as shown in Figure 2 with the spinnerets 12 exposed above the guide plate.

To lift the spinnerets simultaneously the head 20 is provided with a post 21 having a handle 22 which may be readily grasped by the operator 45 drawing the spinnerets partially toward the top of the bath 15.

In starting the flow of the artificial fiber, the spinneret is lifted to the upper position and the starting fiber generally indicated at 24 is grasped 50 by hand and carried over the guide 25. As soon

as all of the fibers have been suitably started in this fashion, the spinnerets may be lowered and the gathered filaments will feed through the apertures in the fixed plate 17 near the surface of the bath. The gathered filaments are taken 5 vertically upward on common axes of the spinneret heads and suitably drawn over the guide by apparatus not shown. It will be seen that the fixed plate 17 thus serves as a separator to assure the gathering of all filaments from all spinnerets 10 and after the lowering of the spinnerets insures a substantially vertical feeding of the filaments through the length of the setting bath. The plate serves in addition to assure uniformity of travel 15 of the various thread groups to the central guide.

If desired, supplemental guides 26 generally shown in Figure 3 may be provided, which supplemental guides can be spring mounted on posts 27 on the fixed guide 17. When the spinneret head 20 is lowered, the spring guides 26 will expand 20 outwardly and, being curved as shown at 29, they will engage the filaments 14 and carry them to a substantially central point forming a right cone 25 from the spinnerets 12. From the guides 26, the filaments pass substantially parallel to the upper 25 guide 25. The filament lengths from the spinneret are thus still further unified for the most effective discharge of the rayon stock.

The invention is adaptable to various forms of rayon production but is especially desirable for 30 production of large denier roving. As one example, the spinnerets are each adapted to discharge in the neighborhood of 15,000 denier and although this may be increased to as high as 45,000 denier, the practical production is best 35 carried out with a greater number of spinnerets of the smaller size. The denier of each filament will vary from one and a half to five depending upon the desired use for the product.

While I have shown a preferred form of embodiment of my invention, I am aware that modifications may be made thereto and I therefore desire a broad interpretation of my invention within the scope and spirit of the disclosure herein and of the claims appended hereinafter. 40 45

What I claim is:

1. In combination with a precipitating bath, a guide, a spinneret head having spinnerets thereon, said guide having apertures through which the precipitated fiber is conducted and means to project the spinnerets through said guide whereby on starting the filaments will be directed through the openings in the guide. 50

2. In combination with a precipitating bath, a guide, a spinneret head having spinnerets thereon, 55

- said guide having apertures through which the precipitated fiber is conducted and means to project the spinnerets through said guide whereby on starting the filaments will be directed through 5 the openings in the guide, and supplemental guide means adjacent the openings to force the filaments into a central position therein when the spinnerets are removed.
3. In combination with a spinneret for artificial fibers, a guide, said guide having an opening through which the fibers from said spinneret are conducted, said spinneret being movable with respect to said guide whereby the spinneret may project through the guide for starting the fibers.
4. In combination with an artificial fiber precipitating bath, a spinneret head, a plurality of spinnerets thereon arranged in a cluster, means to conduct liquid materials to said spinnerets, a guide over which the formed fiber is conducted, 10 an intermediate guide having openings through which separate portions of said fiber is conducted, said intermediate guide being adapted to receive the spinnerets and means for moving said spinnerets into said openings.
5. In combination with an artificial fiber precipitating bath, a spinneret head, a plurality of 15 spinnerets thereon, arranged in a cluster, means to conduct liquid materials to said spinnerets, a guide over which the formed fiber is conducted, and an intermediate guide wholly immersed in the bath having openings through which separate 20 portions of said fiber is conducted, and means to restrict the path of the fiber passing through said openings to the center thereof.
6. In combination with an artificial fiber precipitating bath, a spinneret head, a plurality of 10 spinnerets thereon, means to conduct liquid materials to said spinnerets, a common guide over which the formed fiber is conducted, and an intermediate bath submerged guide for each spinneret and centered with respect thereto substantially on the axis of each spinneret.
7. An artificial fibre precipitation bath comprising a fixed plate having a plurality of angularly disposed openings, means adjacent the openings and movable thereinto to guide a fibre passing through the openings to the center thereof and spinnerets adapted to be projected into said openings and displace said movable guide means therefrom.

NEO S. SERINIS. 25
